(57) **CLAIM**

The ornamental design for a base configured to support an optical scanner, as shown in the accompanying drawings and described above.

DESCRIPTION

FIG. 1 is a top, front perspective view of a base configured to support an optical scanner, in accordance with the present invention.

FIG. 2 is a front elevation view of the base of FIG. 1.

FIG. 3 is a rear elevation view of the base of FIG. 1.

FIG. 4 is a right elevation view of the base of FIG. 1.

FIG. 5 is a left elevation view of the base of FIG. 1.

FIG. 6 is a top plan view of the base of FIG. 1.

FIG. 7 is a bottom plan view of the base of FIG. 1; and,

FIG. 8 is cross-sectional view taken along line 8-8 of FIG. 6 for illustrating the annular recess in the upper surface of the base of FIG. 1. Applicant explicitly disclaims internal features of the cross-sectional view of FIG. 8.

The broken lines shown herein are for illustrative purposes and form no part of the claimed design.
